(57) **CLAIM**

I claim the ornamental design for a ride on vehicle, as shown and described.

DESCRIPTION

FIG. 1 is a front top perspective view of the ride on vehicle according to the new design.

FIG. 2 is a rear bottom perspective view of the ride on vehicle shown in FIG. 1.

FIG. 3 is a front elevation view of the ride on vehicle shown in FIG. 1.

FIG. 4 is a rear elevation view of the ride on vehicle shown in FIG. 1.

FIG. 5 is a left side elevation view of the ride on vehicle shown in FIG. 1.

FIG. 6 is a right side elevation view of the ride on vehicle shown in FIG. 1.

FIG. 7 is a top view of the ride on vehicle shown in FIG. 1; and,

FIG. 8 is a bottom view of the ride on vehicle shown in FIG. 1.

The broken lines in the drawings illustrate portions of the ride on vehicle that form no part of the claimed design.
